US0D1076352S

(12) **United States Design Patent** (10) **Patent No.:** **US D1,076,352 S**
(45) **Date of Patent:** **** May 27, 2025**

(54) **SHOE**

(71) Applicant: **SPECIALIZED BICYCLE COMPONENTS, INC.**, Morgan Hill, CA (US)

(72) Inventors: **Robert Arthur Laurence Cook**, Bayern (DE); **Ashley Gill Sult**, Santa Clara, CA (US)

(73) Assignee: **SPECIALIZED BICYCLE COMPONENTS, INC.**, Morgan Hill, CA (US)

(**) Term: **15 Years**

(21) Appl. No.: **29/869,063**

(22) Filed: **Dec. 20, 2022**

Related U.S. Application Data

(63) Continuation of application No. 29/763,702, filed on Dec. 23, 2020, now Pat. No. Des. 974,005.

CLAIM

The ornamental design for a shoe as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top, and left side perspective view of a shoe embodying our new design.;

FIG. 2 is a left side view thereof.

FIG. 3 is a right side view thereof.

FIG. 4 is a top view thereof.

FIG. 5 is a bottom view thereof.

FIG. 6 is a front view thereof; and,

FIG. 7 is a back view thereof.

Broken lines and half-tone shading are used to illustrate features of the shoe which form no part of the claimed design.

1 Claim, 7 Drawing Sheets
(7 of 7 Drawing Sheet(s) Filed in Color)
